United States Patent Office

Des. 196,489
Patented Oct. 8, 1963

196,489

SHOE SOLE

Theodore Papoutsy, 57 Wingate St., Haverhill, Mass.

Filed May 31, 1963, Ser. No. 75,148

Term of patent 14 years

(Cl. D7—5)

FIG. 1 is a bottom plan view of a shoe sole showing my new design.

FIG. 2 is a side elevational view thereof, the broken line showing of a shoe being for purposes of illustration only.

FIG. 3 is a section taken on the line 3—3 of FIG. 1.
I claim:

The ornamental design for a shoe sole, substantially as shown and described.
